UNITED STATES PATENT OFFICE.

MARION K. OWNBEY, OF SHAWNEE, OKLAHOMA.

ROTARY ELECTRIC SWITCH.

1,107,099.

Specification of Letters Patent. Patented Aug. 11, 1914.

Application filed April 7, 1913, Serial No. 759,489. Renewed February 5, 1914. Serial No. 816,811.

To all whom it may concern:

Be it known that I, MARION K. OWNBEY, a citizen of the United States, residing at Shawnee, in the county of Pottawatomie and State of Oklahoma, have invented certain new and useful Improvements in Rotary Electric Switches; and I do declare the following to be a full, clear, and exact description of the invention, such as will enable others skilled in the art to which it appertains to make and use the same.

This invention relates to improvements in rotary switches and particularly to rotary intermittent gang switches or circuit breakers for electric signs and displaying devices.

One object of the invention is to provide a switch or circuit breaker of this character having an improved construction and arrangement of rotary member and an improved construction and arrangement of pivot levers which are normally and yieldingly held in engagement with the rotary member and are intermittently disengaged therefrom to break the circuits connected therewith at predetermined intervals and for predetermined periods of time.

Another object is to provide a circuit breaker of this character which will be simple, strong, durable and inexpensive in construction, efficient and reliable in operation and well adapted to the purpose for which it is designed.

With these and other objects in view, the invention consists of certain novel features of construction, and the combination and arrangement of parts as will be more fully described and claimed.

In the accompanying drawings: Figure 1 is a perspective view of the displaying device to which my improved circuit breaker is applied; Fig. 2 is a vertical section thereof with parts broken away; Fig. 3 is a vertical cross section through the upper portion of the casing of the device showing the belt or curtain operating mechanism in end elevation; Fig. 4 is an enlarged plan view of the switch or circuit breaker; Fig. 5 is a vertical cross sectional view thereof taken on the line 5—5 of Fig. 4; and illustrating the position of one of the levers of the switch when in electrical contact with the rotary member thereof; Fig. 6 is a similar view taken on the line 6—6 of Fig. 4 illustrating the position of one of the switch levers when disengaged from or out of elec-

trical contact with the rotary member of the switch; Fig. 7 is a vertical longitudinal section through the rotary member of the switch taken on the line 7—7 of Fig. 3; Fig. 8 is a detail horizontal sectional view through the terminal connections of the switch levers taken on the line 8—8 of Fig. 5; Fig. 9 is a vertical sectional view through the same taken on the line 9—9 of Fig. 5; Fig. 10 is a diagrammatic perspective view of the lamp circuits and the switch or circuit closer arranged therein.

In the embodiment of the invention, I provide a case or cabinet C which may have arranged thereon any suitable stationary advertising signs and which is preferably provided with a letter-drop D. The opposite sides of the case or cabinet have therein view openings which are covered by glass panels through which may be observed the signs on the traveling curtains or endless belts B which are engaged with an upper roller R revolubly mounted in suitable hangers H secured to and depending from a partition or shelf S arranged in the upper portion of the cabinet. The curtains or belts are also engaged with lower rollers L which are loosely mounted in suitable brackets in the lower portion of the cabinet as shown. The upper rollers R are suitably geared to a drive shaft s which is revolubly mounted in a bearing bracket depending from one end of the shelf S and which is connected by a train of gears G to a motor M arranged on one end of the shelf S as shown. The arrangement of the train of gears G is such that the curtains or belts will be driven at the desired speed by the motor as will be readily understood.

Arranged in the cabinet C in any suitable manner and at any desired positions are electric lamps a which may be white or of various colors as desired. The lamps a are arranged in branch circuits b which are connected with a main circuit c, said branch and main circuits being connected with my improved switch or circuit closer whereby the lamps are periodically or intermittently lighted and extinguished. The switch or circuit closer comprises a rotary member 1 and a series of pivotally mounted levers 2. The rotary member 1 of the switch comprises a drum or cylinder 3 formed of wood or any suitable non-conducting material and having a centrally disposed shaft 4 the ends of which are journaled in suitable bear-

ing standards 5 fixed on the shelf S in the upper portion of the cabinet. The cylinder 3 is provided with a metallic shell or casing 6 having on one end an annular flange 7 which overlaps one end of the cylinder 3 and with which is engaged a current conducting brush 8 suitably secured to one of the bearing standards 5 of the cylinder and to which is connected one terminal of the main circuit *c* of the lamps. Arranged in annular rows and spaced any desired distances apart in the shell or casing 6 of the cylinder are circular apertures 9 in the center of each of which is a circuit breaking stud 10. The studs 10 are preferably driven into the cylinder 3 and have their outer ends projecting suitable distances beyond the outer surface of the shell, said projecting ends of the studs being preferably beveled as shown. The apertures 9 in the shell 6 are of such size as to positively clear the studs so that there will be no possibility of the electric current passing from the shell to the studs which are thus insulated from the shell.

One end of the shaft 4 of the cylinder projects a suitable distance beyond one of the standards 5 and has fixed thereon a sprocket gear 11 which is connected by a sprocket chain 12 to a sprocket gear 13 on the drive shaft *s* which operates the endless sign displaying curtains or belts. By thus connecting the cylinder or rotary member 1 of the switch with the shelf 5 it will be seen that the rotary member will be driven by the motor *M* and that the speed of the rotary member 1 may be governed or controlled by the size of the gears 11 and 13.

The levers 2 are pivotally mounted intermediate their ends in the bifurcated upper ends of a series of binding posts 14 which are spaced suitable distances apart and secured to a base plate 15 formed of insulating material and which is fastened to the shelf S in any suitable manner and at a suitable distance from the rotary member 1 of the switch. To the binding posts 14 are connected one terminal of the branch lamp circuits *b* the opposite terminals of which are connected with the main circuit *c* as clearly shown in Fig. 10 of the drawing. Each of the levers 2 is preferably in the form of a flat metal bar having its forward end twisted or turned to bring the flat side of the plate parallel with the surface of the cylinder 3, said twisted or turned ends of the levers being preferably curved and having their extremities beveled as at 16 to form an enlarged contact surface which is normally held in engagement or contact with the outer surface of the shell 6 of the cylinder by coiled springs 17 which are connected to the outer portion of the levers 2 and to the binding posts 14 as shown. The levers 2 are arranged at such

positions on the base plate 14 that their beveled extremities engage the surface of the cylinder in the planes of the rows of circuit breaking studs 10 so that when the cylinder is revolved the outer ends of the studs are brought into successive engagement with the beveled extremities of the levers thereby disengaging said levers from the shell of the cylinder to intermittently break the circuits of the lamps.

By spacing the studs 10 at different distances apart in the annular rows on the cylinder it will be seen that the breaking of the circuits may be made to occur at longer or shorter intervals as desired and it will also be seen that by increasing the width of the beveled extremities 16 of the levers that the circuits may be held open for a longer or shorter period of time, as desired. As soon as the outer ends of the studs 10 pass the beveled extremities of the levers the spring 17 will immediately swing said extremities into engagement with the shell 6 and complete or close the circuit. The outer ends of the levers 2 are also preferably twisted or turned in the same manner as the contacting ends of said levers, thereby forming handles 18 by means of which the levers may be manually disengaged from the rotary member of the switch when desired.

From the foregoing description taken in connection with the accompanying drawings, the construction and arrangement of the device will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. In a switch of the character described, a rotary member comprising a cylinder of non-conducting material, a metallic shell inclosing said cylinder, a brush having a continuous electrical connection with said shell and forming one terminal of the main wire of an electrical circuit, a series of circuit breaking studs carried by said cylinder and insulated from said shell, branch circuit wires having one terminal thereof connected with said main circuit wire, and the other terminals normally in electrical contact with the shell on said cylinder and adapted to be intermittently disconnected therefrom by said studs.

2. In a switch of the character described, a rotary member comprising a cylinder of non-conducting material, a metallic shell inclosing said cylinder and having therein series of apertures, an annular contact flange on said shell at one end of the cylinder, a

- contact brush having a continuous engagement with said flange and forming one terminal of the main wire of an electric circuit, a series of circuit breaking studs arranged in said cylinder and projecting through the apertures in said shell whereby said studs are insulated from or out of electrical connection with said shell, branch circuit wires having one terminal connected with said 10 main circuit and having their other terminals normally in electrical contact with the shell on said cylinder and adapted to be intermittently disconnected from said shell by said studs.
- 15 3. In a switch of the character described a rotary member comprising a revolvably mounted cylinder of non-conducting material, a shell inclosing said cylinder, a brush having a continuous electrical contact with said shell and forming one terminal of the main wire of an electric lamp circuit, series of circuit breaking studs carried by said cylinder and insulated from said shell, a series of binding posts, a series of branch current conducting wires having one end connected with the main wire and lamps of the circuit and their opposite ends with said binding posts, contact levers pivoted on said binding posts and forming the terminals of said branch wires, and springs to yieldingly hold one end of said levers normally in electrical contact with said cylinder and in line with the studs thereon whereby the engagement of the studs with said levers will intermittently break the circuits of the lamps. 35
4. In a switch of the character described, a rotary member forming one terminal of an electric circuit, circuit breaking projections carried by and insulated from said member, a series of binding posts, branch current 40 conducting wires connected with said posts and with said electric circuit, a series of contact levers pivoted on said binding posts and forming the terminals of said branch wires, said levers comprising bars having 45 one end turned to present a flat surface to said rotary member, said turned end having its extremity beveled to form a broadened contact surface, springs connected with said levers whereby the extremities thereof are 50 held in yielding engagement with the surface of said rotary member, and means whereby said rotary member is revolved to bring the circuit breaking projections thereon into successive engagement with the extremities of said levers thereby intermittently disconnecting the latter from said 55 rotary member.
- In testimony whereof I have hereunto set my hand in presence of two subscribing witnesses. 60
